UNITED STATES PATENT OFFICE.

HENRY EDWIN PARSON, OF NEW YORK, N. Y.

GRATE FOR MECHANICAL STOKERS.

992,685.

Specification of Letters Patent. Patented May 16, 1911.

Original application filed February 24, 1905, Serial No. 247,083. Divided and this application filed October 18, 1905. Serial No. 283,285.

To all whom it may concern:

Be it known that I, HENRY E. PARSON, a citizen of the United States of America, and resident of the city of New York, county 5 and State of New York, have invented certain new and useful Improvements in Grates for Mechanical Stokers, of which the following is a specification.

My invention relates to certain new and useful improvements in grates and the object 10 of my invention is to produce a grate, particularly adapted for use in connection with a mechanical stoker and with which any kind of coal may be burned with equally 15 good effect.

The grates are of peculiar construction 20 having removable bars with ash pockets parallel to the length of the fire in their upper surface and an ash pocket located transverse 25 of the grate upon its rear edge. These grates are inclined and I provide a dam located at the lower end thereof to control the thickness of the fire and the speed with which it will travel down the grate.

25 This application is a division of my application Serial No. 247,083, filed Feb. 24, 1905.

Referring to the drawings wherein the same part is designated by the same reference numeral wherever it occurs, Figure 1 30 is a vertical longitudinal section of the grate. Fig. 2 is a top plan view partly broken away, showing the grate and frame and its operating mechanism. Fig. 3 is a perspective view of one of the grates which are driven 35 and used as ash and fuel pushers. Fig. 4 is a vertical transverse section of the same. Fig. 5 is a vertical longitudinal section of the same. Fig. 6 is a perspective view of 40 one of the detached bars. Fig. 7 is a vertical elevation, partly in section of the supporting rollers.

I have shown my grate as adapted for use 45 in connection with a furnace of the type shown in my application Serial No. 247,083, above referred to, and I hereby refer to said application for a detail description of all parts which are shown, but not described in this application, or which are entirely omitted therefrom. In this application, I confine 50 my description and claims to the grate mechanism and will not describe the other parts which enter into the construction of a furnace.

1 designates the grate as a whole and it is 55 composed of a series of grate sections 2 and

3. The sections 2 are located alternately between the sections 3 and overlap them so that the sections form a flight of steps from the top to the bottom of the grate. The sections 2 are movable while the sections 3 60 are stationary. The sections 2 and 3 are identical in construction except that at the lower end of the flight, the sections 2 are thicker than those higher up. The sections are shown in detail in Figs. 3 to 6 inclusive. 65 Referring to these figures, Fig. 3 shows one of the sections 2, one half of the section having the removable bars removed. This section consists of a frame 4 divided into two portions by partitions 5 and having on its 70 interior undercut dove-tail grooves 6 in which are fitted the detachable grate bars 7. 8 is an ash pocket on the rear edge of the grate frame which is a pushing edge. This ash pocket 8 serves to protect the edge of the 75 grate frame from being burned by the fire. Referring to Figs. 4, 5 and 6, the construction of the grate sections will be understood. The bars 7 have beveled ends to fit the undercut groove 6, and deep pockets in their 80 top surfaces. The bottoms of the bars are extended downward so as to absorb the heat from the top and thus prevent the burning of the upper edges. The pockets become filled with ash and protect the upper surface 85 from the fire. 9 are slots cut in the undercut groove 6 at one end and through which the bars 7 are inserted. The last bar is secured in place by pin 10. 11 are pairs of lugs on the lower edge of the frame of 90 the grate on each side adapted to receive the device by which the sections are supported at their front ends and by which they are reciprocated. The grate sections 3 resemble 95 in structure the sections 2, but are stationary and are mounted at their rear ends in lugs or seats 12, which project through the bearing bars of the furnace carrying the stationary sections, as is best shown in Fig. 1.

The grate, as has been before stated, is 100 composed of movable sections and stationary sections. A suitable number of movable sections are of equal thickness, while another part of the movable sections, suitable in number for given fuel conditions are 105 made thicker than are the stationary sections to which they are adjacent. The greater thickness of some of the sections, as above mentioned, all of which are given the same throw irrespective of their thickness, 110

will cause a greater quantity of ash and fuel lying upon them to be moved forward and downward with each stroke than will be the case with sections which are less thick. This 5 will produce at the proper part of the fire a suitable thickness of the fire and permit of a suitable supply of air for the best combustion and insure the complete burning of the coal before it passes off the grate.

10 13 is a grate supporting and reciprocating frame which is shown in Figs. 1 and 2. The frame is provided with flanges 14, two for each side, projecting laterally from the sides of the frame and resting upon the supporting rollers 15. Upon the upper surface of the sides of the frame and projecting vertically are a series of fingers 16 which are provided on their upper ends with heads of suitable shape. To the frame 13 is connected 20 a rod 17 which is actuated in a suitable manner, for instance, in the manner shown and described in my application above referred to, so as to give the frame a reciprocating movement. The grate frame is supported in 25 an inclined position below the grate bars, but the flanges or lugs are horizontal, while the fingers are vertical and engage the movable ends of the grate bars between the lugs 11.

The construction of the supporting rollers 30 by which the grate frames are supported is shown in detail in Fig. 2. Referring to this figure, 18 is a grate frame divided into three sections by the bearing bars 19 which are expanded at their lower edges to form bosses 35 20. The bosses are recessed at 21 on each end and perforated through the bottom of the recesses to form a bearing for the axles 22. On each of the axles 22 are fitted the grate frame supporting rollers 15 which 40 have hubs 23 which center the recesses 21 and serve to protect the axles 22 from ash. The central bearing bars 19 are provided with double bosses and supporting rollers, while the side bars have but one pair. 45 24 is an inclined table abutting the frame 18 and supported upon the main grate support which rests upon the division wall. To the rear edge of the table 24 is pivoted an ash dam 25 which overhangs the ash pit and 50 is connected at its lower side to a push rod pivoted to the dam at one end and protrud-

ing through the front wall at its other. At its front end, it may be provided with any suitable means for operating the same, such as a hand wheel 26 engaging the threaded end of the rod by which the dam may be set at any desired angle, so as to hold back the ash and fire, and give to the fire any desired thickness upon the grate. 55

The operation of my device will be apparent from the foregoing description. 60

While I have described what I believe to be the preferred form of my invention, I desire to have it understood that many changes may be made in the form, construction, and arrangement of parts without departing from the spirit of my invention. 65

What I claim as new and desire to secure by Letters Patent is:

1. In a mechanical stoker, the combination 70 of a series of grate sections overlapping each other to produce an inclined stepped grate, alternate sections being stationary and alternate sections reciprocating and resting at their forward ends on the stationary sections, an inclined frame below the grate provided with vertically projecting fingers which engage and support the ends of the reciprocating sections; a series of supporting rollers mounted adjacent to the frame and in a plane parallel to it, roller supports having recesses in which the rollers engage, and means supporting the frame upon the rollers whereby the frame may reciprocate horizontally and still maintain its inclination. 75 80

2. In a mechanical stoker, a fuel advancing grate having a passage over the lower end thereof to the ash pit, a dam at the lower end of the grate protruding upward into said passage, and means for adjusting the 90 position of the upper edge of said dam and securing said upper edge in various adjusted positions to restrict said passage, and thereby to regulate the fuel carrying capacity of the grate. 95

Signed by me at Birmingham, Alabama, this 12th day of October, 1905.

HENRY EDWIN PARSON.
